Application June 25, 1941, Serial No. 399,635

3 Claims.

(Cl. 220—1)

This invention relates to an improvement in ice cream containers, and more particularly in containers of the type used by dispensers of ice cream to hold cans of ice cream in the refrigerator.

Ice cream is distributed in bulk in cans to restaurants, drug stores and other retail establishments, which cans are stored in a refrigerator and from them the ice cream is served. Such cans are usually cylindrical and were originally made of metal, but while metal cans are still in use, the common practice today is to make the cans of pasteboard, pulp or the like.

The primary object of this invention is to provide containers which are placed in the refrigerators and into which the cans are freely set and held in position for easy removal of servings of the ice cream, usually by spoon or scoop. Features of this invention include the provision of means which restrain the tendency of the cans to rotate as the servings are removed, of prongs which are embedded in the walls of the cans when of pasteboard or other perforable material, and of removable supports by which the cans may be held in easy serving position.

One embodiment of this invention will be set forth in the following description and in the drawings which form a part thereof, and in which

Fig. 1 is a view in side elevation of a container embodying this invention;

Fig. 2 is a top plan view of such container;

Fig. 3 is a sectional view, taken along the line 3—3 in Fig. 1, of the latching means in the open position;

Fig. 4 is a sectional view, taken along the line 4—4 in Fig. 1, illustrating the support for a can; and

Fig. 5 is a view in side elevation of such support.

The container 10 shown in the drawings comprises a base 11 and a pair of shells or cylinders 12 mounted on the base 11 and preferably connected thereto by rivets or similar means. The cylinders 12 are similar in construction, each being of resilient sheet material, for example, stainless steel, and of a size to receive two cans 15 each containing two and a half gallons of ice cream. In the drawings the left-hand shell or cylinder contains two such cans while the right-hand shell or cylinder contains a single can 15 resting upon a suitable support, to be described later.

The wall of each cylinder 15 is divided by a horizontal slot 16 (extending through substantially half the periphery) and preferably disposed in a plane which is approximately one-fourth the distance from the top to the bottom of the cylinder into an upper and a lower section. The lower section has a plurality of holes 17 arranged in a horizontal row substantially at the mid-height of the cylinder, and also has openings 18 at

the bottom thereof left by the formation of tongues 19 which are bent outwardly and downwardly and receive the rivets for securing the cylinder to the base 11.

5 Each container 12 has a periphery greater than that of the cans it encloses so that the walls of the cans are in most part out of contact with the wall of the cylinder and the holes 17 and openings 18 admit air freely so that the cylinders are ventilated. Moreover, the space between the walls of the cans and the containers is sufficient to admit the bails, tongs, or other instruments by which the cans are handled. Since the ice cream is usually removed by scoops, spoons or the like, it has heretofore been necessary to hold the cans stationary by hand. This is difficult, particularly when the cans are full.

In accordance with this invention the upper section of each container is designed to form a contractible collar 20 by which the upper can is frictionally engaged peripherally to restrain the tendency of the can to rotate. Preferably the collar is of appreciable vertical depth to support the wall of the can and prevent injury to it by the scoops or spoons. The form of collar 20 shown in the drawings includes a main portion 20a which forms a continuation of the lower section and a pair of arms 21 and 22, the inner ends of which are integral with or attached to the main portion 20a.

20 The lower edges of the arms 21 and 22 are bounded by the slot 16 and their proximate ends are separated by a gap extending downwardly from the top of the cylinder to the slot, said gap being disposed substantially symmetrically with respect to the remote ends of the arms and resulting from the removal of a portion of the material of the upper section of the container. The upper edges of the main portion 20 and of the arms 21 and 22, and the proximate edges of the arms 21 and 22, are reinforced by bands 23 and 24, consisting, in the illustrated embodiment, of bent-over flanges of the material.

25 The arms 21 and 22 are connected by a strap 25 passed under portions 26 and 27 respectively of the bands 24. A portion of the arm 21 is struck outwardly to form an integral loop 28 and one end of the strap is passed through this loop and its tip 29 is bent back over the outer face thereof. A latch 30, pivoted between brackets 31 fixed to the arm 22, is connected to the other end of the strap 25 by a pin 32 passed through a loop 33 formed at that end of the strap.

30 The proximate edges of the arms 21 and 22 are bent inwardly at one or both corners to form inwardly directed prongs 35. When the latch 30 is open, as shown in Fig. 3 and on the left-hand cylinder in Figs. 1 and 2, the arms 21 and 23 are in register with the wall of the lower portion of the cylinder so that the cans 15 may freely enter

the cylinder. Upon closing the latch 30, the upper can 15 is engaged closely by the arms 21 and 22 so that its tendency to rotate is frictionally opposed. If, as is now usually the case, the walls of the can are of pasteboard, wood, or other penetrable material, and the prongs 35 are employed, such prongs will be embedded therein and serve as a further and positive means for holding the can at rest. The ice cream can thus be easily removed from the can by a scoop, spoon, or other implement without the necessity of manually holding the can stationary.

The amount of force exerted by the arms 21 and 22 is determined by the length of the strap 25 between the loop 28 and the latch 30. This length can easily be varied by increasing or decreasing the length of the tip 29 which is bent over the loop 28. When the length of the strap 25 has been determined, the portion 26 of the band 24 on the arm 21 is forced inwardly against the strap 25 to prevent any movement thereof relative to the loop 28. The portion 27 of the band 24 on the arm 22 is, however, raised sufficiently to serve as a guide for the strap while permitting its free movement thereunder.

In most cases two cans will be placed in the cylinder, one on top of the other, as in the left-hand cylinder in Fig. 1. However, should there be only one can in the cylinder, it may be positioned within the upper part of the cylinder by a supporting spider 40 (Fig. 5) which engages the ventilating holes 17. The support 40, as shown in Figs. 4 and 5, comprises a pair of parallel bars 41 connected by a diagonal bar 42. In the lower edges of the bars 41 near the ends thereof are formed notches 43 which receive the lower peripheries of the holes 17 and thus hold the support 40 in position.

While one embodiment of this invention has been shown and described in detail, it will be understood that the invention is not limited thereto and that changes may be made in the elements of the described embodiment or other embodiments may be made without departing from the spirit and scope of the invention as set forth in the following claims.

I claim:

1. A container of the kind which is employed for positioning a tubular ice cream dispensing carton in a refrigerating chamber and which comprises a base and a vertically disposed, open-topped cylinder of resilient sheet material, said cylinder being of a normal internal diameter exceeding that of the carton which it is designed to hold, the cylinder being of a depth sufficient to hold a plurality of superposed cartons, characterized in that the cylinder has a circumferential slit extending approximately half way around it at a distance from its upper edge such that the slit is intermediate the top and bottom of the uppermost of said cartons, and a vertical gap reaching from its upper edge to the slit, the gap being disposed substantially symmetrically with respect to the opposite ends of the slit, the slit and gap defining two peripherally extending, flexible, resilient arms integrally joined at their remote ends to the body of the cylinder and whose proximate ends are separated by the gap, the proximate ends of the arms having inwardly directed prongs designed positively to engage the carton thereby to prevent its rotation, and re-

leasable clamping means uniting the arms and operative to draw their proximate ends toward each other thereby to constrict them about a carton disposed within the cylinder and to force their prongs into holding engagement with the carton.

2. A container of the kind which is employed for positioning a tubular ice cream dispensing carton in a refrigerating chamber and which comprises a base and a plurality of vertically disposed, open-topped cylinders each of resilient sheet material and each of a normal internal diameter exceeding that of the containers which they are designed respectively to hold, means rigidly securing the cylinders to the base, each cylinder being of a depth sufficient to hold a plurality of superposed cartons, characterized in that each cylinder has a circumferential slot disposed in a plane substantially one-fourth the distance from the top to the bottom of the cylinder, and each cylinder having a vertical gap extending from its top edge to the slot, the slot and the gap defining a pair of peripherally extending, flexible and resilient arms integrally united at their remote ends to the cylinder and having their proximate ends spaced apart by the gap, each cylinder having a plurality of peripherally spaced apertures centered on a plane substantially half way down from the top edge of the cylinder, a supporting spider comprising parallel bars united by a diagonal connector, each of said bars having opposite end portions each designed to enter one of the apertures in the cylinder wall, the spider, when so positioned, constituting a support for holding a carton in the upper half of the cylinder, each cylinder being provided with clamping means operative to draw the proximate ends of its arms inwardly into frictional holding contact with a carton in the upper part of the cylinder.

3. A container of the kind which is employed for positioning a tubular ice cream dispensing carton in a refrigerating chamber and which comprises a base and a cylindrically curved, open-topped, hollow shell of resilient sheet material secured at its lower edge to the base and of a horizontal sectional area exceeding that of the carton which it is designed to hold, characterized in that the shell has a peripheral slot spaced from its upper edge a distance substantially equaling one-half the depth of the carton, the shell also having a gap extending from its upper edge to the slot, the gap and slot defining two arms whose proximate ends are bounded by the gap and whose remote ends are integrally joined to the body of the shell, one of said arms having an attaching loop at a point spaced from the free end of the arm, a flexible strap having one end portion extending through said loop and bent, thereby to connect the strap to the arm, each of said arms having a loop closely adjacent to its free end, the strap extending across the gap and through both of said latter loops and to a point adjacent to the remote end of the other arm, and a latch lever pivotally secured to said latter arm and to the free end of the strap, said latch lever being actuatable to apply constricting force to the strap for drawing the proximate ends of the arms toward each other thereby to clamp them firmly against a carton arranged within the upper part of the shell.

HOMER J. MESSIER.
